ELECTRIC SWITCH

Filed June 25, 1926

UNITED STATES PATENT OFFICE.

HARRY A. DOUGLAS, OF BRONSON, MICHIGAN.

ELECTRIC SWITCH.

Application filed June 25, 1926. Serial No. 118,540.

My invention relates to switch structures that are mounted upon panel boards, such, for example, as the dash boards of automobiles for the purpose of conveniently controlling electric current conducting circuits.

The body of the switch casing, in accordance with my invention, is carried upon and extends from one side of the panel board and fuse clips are provided upon the portion of the switch casing that is perpendicular or angular to the panel board and positioned to be readily accessible from beneath, above or on one side of the panel board for the insertion and removal of fuses. The bridging mechanism of the switch structure is in direct relation with one end of a fuse or each of several fuses thus mounted, the other end of such fuse being equipped for connecting the same into the circuit protected thereby.

The invention also relates to the unitary construction of switch contacts and fuse clips.

The invention will be more fully explained in connection with the accompanying drawing as employed in an automobile and in which Fig. 1 is a front view of a switch structure to which my invention may be applied; Fig. 2 is a rear view thereof with the fuse clips and fuses assembled with the casing in accordance with the invention; Fig. 3 is a side view of the switching mechanism with the dash board shown in section and broken away; Fig. 4 is a longitudinal sectional view of the switch structure; and Fig. 5 is a longitudinal sectional elevation through that portion of an automobile where the dash board and contiguous parts are located, the switch which is arranged according to my invention being shown in side elevation upon the dash board.

The casing illustrated is inclusive of a body of insulation in the form of a cup having a cylindrical side wall 1 and a rear or bottom wall 2 in integral formation. The front metallic end wall 3 of the casing constitutes a closure that is placed upon the rim of the cup and is held in assembly with the cup by means of the riveting pins 4. A cover plate 5 is riveted to and in front of the casing end wall 3 also by the aforesaid riveting pins 4. A handle 6 is formed with a flange 7 which is received in the space between the front end wall 3 and said cover plate 5. The handle is provided with prongs 8 which pass through openings 9 formed in the casing end wall 3 and are received in notches 10 formed in the insulating ring 11, this ring thus accompanying the handle in the turning movements of the latter. The ring is pressed toward the casing end wall 3 by means of a coiled spring 12 that bears against the ring. A metallic band 13 surrounds the ring and is provided with forwardly extending and inwardly sloping tongues 14 which constitute contacts that are complementary to various contacts 15, preferably formed of strip metal, which are shown as being included in the horn circuit, the bright head-light circuit, the dim head-light circuit and the tail-light circuit, as will be well understood by those familiar with the art. The contacts 14 are formed with depressions 14' and the ring 11 is formed with depressions in the spaces between the contacts 14 to receive depressed portions of the contacts 15 whereby the ring is held in the position to which it is turned by the handle to maintain the desired circuit adjustment effected by turning the handle. The various circuit portions that terminate in the contacts 15 also include spring clips 16 which receive end portions of the fuse devices 17 whose remaining end portions are received in the spring clips 18 that are mechanically and electrically assembled with the contacts 15 whereby the circuit portions terminating in the contacts 15 are caused to include said fuse devices. The contacts 15 have integral continuations that extend through the switch casing and constitute means for anchoring the fuse clips that are electrically connected therewith. The clips 16 are provided with separately formed base portions 16' that are provided with binding screws 19 that are employed to mechanically and electrically assemble the wires 20 with the clips. The clips 16 and 18 are secured upon the cylindrical side wall of the switch casing which is angular to the dash board 21 through which the body portion of the casing extends to the front thereof, the cover plate 5 also passing through the dash board and being clamped against the front or forward face thereof by means of the mounting screws 22, the handle 6 being upon the rear or backwardly facing side of the dash board in accordance with common practice. The dash board terminates short of the automobile floor portion 23 to afford access to the brake lever 24, the clutch lever which is not shown, and the accelerator 25. The wires 20 are assembled with the casing

and pass through the wall 26 of the automobile bonnet. The fuse devices are located upon and parallel with the lower portion of the cylindrical side of the switch casing 5 and in front of and angular to the dash board so as to be readily reached from beneath and in front of the forward face of the dash board as will be understood by reference to Fig. 5. The fuse devices may thus 10 readily be inserted and replaced by reaching beneath and behind the panel board. The spring clips 16 are assembled with the cylindrical wall of the casing by means of the rivets 27, these rivets passing through the bottoms of the clips and their separately formed base portions 16', these base portions intervening between the bottoms of the clips and the cylindrical wall of the casing and having holding ears 16" formed thereon, the bottoms of the clips being received between these holding ears and the portions of the parts 16' that intervene between the bottoms of the clips 16 and the cylindrical casing wall, as indicated most clearly in 15 Fig. 4. The bottoms of the spring clips 18 are assembled with the cylindrical wall of the switch casing by means of the U-shaped continuations 15' of the contacts 15, the base portions of said contact continuations clamp- 20 ing the bottoms of the clips 18 in place, the sides of said contact continuations passing through the cylindrical side of the casing and being clinched into engagement therewith upon the interior of the casing. The 25 contacts 15 and the spring clips 18 may be formed in unitary structures by striking the ears 15" from the contact continuations 15' and interposing the bottoms of these clips between the parts 15" and the portion of part 15' from which these parts are struck. The contacts 15 are thus mechanically and electrically unitary with the clips pertaining thereto and have direct electrical connection therewith. 30 Where the switch is in the form of a combined ignition and lighting switch, the handle 6 is formed with a circular opening which is coaxial with the hub of the handle, this circular opening receiving the forward end of a tumbler barrel 28 through which a key may be inserted to adjust tumblers 29. The tumbler barrel may be held from rotation when it is turned to bring the tumblers in register with the openings 30 formed in opposite sides of the locking sleeve 31 which is fixedly carried by the 35 front casing end wall 3 and projects within the casing, the tumblers falling into locking position when the key is withdrawn. When the tumbler is to be turned, the key 40 is inserted to withdraw the ends of the tumblers from the openings 30, the key thereafter being turned to turn the tumbler barrel. As is well known, when the tumbler barrel is locked from rotation, the ignition 45 circuit is open and when it is turned from its locked position, the ignition circuit is closed. The switching means illustrated for controlling the ignition circuit is inclusive of contacts 32 carried by and passing 50 through the rear end wall 2 of the casing, the contacts 33, in the form of rearwardly bulged portions of a metallic ring 34, and an insulating ring 35 upon which the ring 34 is clipped and which is in splined or sliding 55 connection with an extension of the tumbler barrel so as to be turned by this barrel whenever the key is turned. The spring 12 in addition to pressing the ring 11 forwardly also presses the ring 35 rearwardly 60 so that it serves not only to establish firm electrical engagement between the contacts 14 and 15 but also to establish firm electrical engagement between the contacts 33 and 32. 65 Changes may be made without departing from the invention.

Having thus described my invention, I claim:

1. The combination with a panel board; of a switch casing carried by the panel board and having its body portion extending upon one side of said board angularly thereto; switching mechanism within the casing; a handle upon the other side of said board and in controlling relation to the switching mechanism within the casing; clips upon the lower part of the casing side wall that is angular to the dash board and on the exterior of the casing; and a fuse held by said clip. 90
2. The combination with a switch casing; of switching mechanism within the casing; clips upon the exterior of the casing, a contact of the switch having an integral continuation extending through the casing and serving as an anchorage for a clip with which it is in direct electrical connection; and a fuse held by said clips. 105

In witness whereof, I hereunto subscribe my name.

HARRY A. DOUGLAS.
